3 Claims. (Cl. 313—54)

The present invention relates to electronic apparatus employing radioactive substances such as radio-isotopes.

It is an object of the present invention to provide improved electronic apparatus wherein radioactive materials are employed as emitters.

It is a further object of the invention to provide improved television apparatus.

Briefly, to achieve its objectives the invention contemplates the provision of a television tube employing a radioactive emitter and thereby avoiding the need for power supplies for emission purposes, this savings facilitating the manufacture of portable television equipment.

Features and advantages of the invention will be made clear in the following explanation which is made with reference to the accompanying drawings in which:

FIG. 1 is a cross sectional view of one of the embodiments of a Braun tube apparatus according to the present invention;

FIG. 2 is a diagrammatic perspective view of a device for transmitting β -rays to a photoelectric fluorescent screen;

FIG. 3 is a cross sectional side view of an apparatus similar to FIG. 1 but provided with a device for the removal of γ -rays;

FIGS. 4a and 4b illustrate a perspective view and a cross-sectional view of a device for amplifying detected waves according to the invention;

FIGS. 5a and 5b are a perspective view and a cross-sectional view similar to those of FIG. 4 but of a modification; and

FIG. 6 is a cross sectional view illustrating a television camera apparatus according to this invention.

In FIG. 1, the illustrated apparatus consists of a display tube having a cathode container 1 in which a radio-isotope 2 is accommodated. This container 1 is made of a material which effectively shields rays emitted from the isotope, for example, lead, but has a hole 1' in the front surface through which rays are allowed to proceed when a cover 3 slidably provided to cover said hole is removed by the operation of a knob 4, and thus it serves as a cathode emitting β -rays. For the isotope 2, any isotope which emits β -rays and is readily available can be used.

β -Rays emitted from the isotope are controlled by a grid 5 which receives the information to be displayed and a horizontal and vertical control electrode 6 and proceed to a fluorescent screen 7 to form an image on the surface of said fluorescent screen 7.

FIG. 2 diagrammatically illustrates a flat device for deflecting β -rays emitted from an isotope in a container 1a in order to project the β -rays to a desired spot on a fluorescent screen 7a. The β -rays are deflected to take a tortuous passage in the flat body as illustrated by the chain line.

2

FIG. 3 illustrates an apparatus provided with a device for the removal of γ -rays when an isotope such as St 90 is used which emits γ -rays together with β -rays. In this device, β -rays and γ -rays are emitted from the container 1b via opening 1'b in an inclined direction in relation to the fluorescent screen 7b, but the β -rays are deflected by a magnet 8b so that they proceed to the fluorescent screen 7b while the γ -rays take a different course. As well known in the art, γ -rays are not deflected by a magnetic field and hence the β -rays are separated from the γ -rays by the action of the magnet 8b. This embodiment is further provided with a cover 3b and grids 5b.

FIGS. 4a and 4b illustrate an embodiment which is used as a detected wave amplifier. A container 1c of an isotope is removably accommodated in a circular vessel consisting of two layers 9c and 10c. The layer 9c surrounds the container 1c and serves as a grid and element 10c serves as an anode. The assembly of the elements 1c, 9c and 10c is provided with legs 11c and may be connected to various outside devices. A signal is introduced to the grid 9c through a wire G by means of one of the legs 11c which is connected to said wire G. Under the influence of the input signal, the quantity of β -rays emitted from the isotope is controlled and an amplified output is taken from anode 10c and is transmitted to a suitable output device (not shown) through a wire P which is connected to another of the legs 11c.

FIGS. 5a and 5b illustrate a similar device but this device has a flat rectangular shape instead of a cylindrical form. In this embodiment, the container 1d is flat and rectangular and is enveloped in a thin and rectangular grid 9d and, over the assembly of the isotope container 1d and the grid 9d, a plate 10d is laid as shown in the drawing. The input signal introduced to a grid 9d is amplified and is transmitted to another suitable device through a line P similar to the arrangement in the apparatus of FIGS 4a and 4b.

FIG. 6 is a sectional view illustrating an isotope container 1e used as a cathode in a television camera tube. β -Rays emitted from the isotope 2e in a container 1e are passed through a target 12 and a grid 13 is interposed between this target and a photoelectric screen 14 (which receives the image to be scanned) a control field being formed by electric coils 15 and electrodes 16 arranged as diagrammatically illustrated in FIG. 6.

This camera tube works generally in the manner of a conventional image orthicon. The rays emitted by container or source 1 are focused by coils 15. Screen 14 converts a visible image into transmitted electrons which pass to target 12 under the influence of electrodes 16 and grid 13 so that, due to secondary emission an electrostatic image is formed on target 12 which when scanned by the focused ray emits an electron collected by anode A coupled to output device O.

As explained above, the apparatus according to the present invention has various advantages, among which the following may be particularly mentioned:

- (1) The apparatus is light, compact and strong;
- (2) The apparatus does not need an electric source for the emission of electrons;
- (3) The apparatus is less expensive but capable of performing with excellent results.

Apparatus of the invention will provide an inexpensive light and compact portable TV unit which is easy to handle with no fear of damage. This invention is believed, therefore, to be a significant valuable invention which has a very wide field in use.

What is claimed is:

1. Apparatus comprising a target responsive to beta rays for transducing electronic and visual signals, a source of beta rays operatively disposed with respect to said target for directing said rays thereat, first means operatively associated with said source to cause said rays to scan said target, and second means operatively associated with said source for transducing the intensity of said rays and visually perceptible information on said target such that said intensity and information are correlated to said electronic signals.
2. Apparatus as claimed in claim 1 wherein said second

4

means converts the visually perceptible information into said electronic signals.

3. Apparatus as claimed in claim 1 wherein said second means converts the electronic signals into visually perceptible information on said target.
